Primary Examiner — Brett Miller*Assistant Examiner* — Jasmine L. Comedy(74) *Attorney, Agent, or Firm* — Millen, White, Zelano & Branigan, P.C.; William Nixon(57) **CLAIM**

The ornamental design for a lighting device, as shown and described.

DESCRIPTION

FIG. 1 illustrates a front perspective view of a lighting device showing my new design;

FIG. 2 illustrates a front elevational view thereof;

FIG. 3 illustrates a rear elevational view thereof;

FIG. 4 illustrates a left side elevational view thereof;

FIG. 5 illustrates a right side elevational view thereof;

FIG. 6 illustrates a top plan view thereof;

FIG. 7 illustrates a bottom plan view thereof; and,

FIG. 8 illustrates another front perspective view thereof.

The broken lines shown throughout the views depict unclaimed portions of the lighting device and form no part of the claimed design.

1 Claim, 8 Drawing Sheets(56)
